CHARLES WILEY, OF HANNIBAL CENTRE, NEW YORK.

Letters Patent No. 88,106, dated March 23, 1869.

IMPROVEMENT IN ALARM-BELLS.

The Schedule referred to in these Letters Patent and making part of the same.

To all whom it may concern:

Be it known that I, CHARLES WILEY, of Hannibal Centre, in the county of Oswego, and State of New York, have invented a new and useful Improvement in Burglar-Alarm; and I do hereby declare that the following is a full, clear, and exact description thereof, which will enable those skilled in the art to make and use the same, reference being had to the accompanying drawings, forming part of this specification, in which—

Figure 1 is a front view of my invention, and

Figure 2 shows the same, with the hammers and face-plate removed.

Figure 3 shows its application to a door.

Similar letters of reference indicate like parts.

This invention relates to a new and improved construction of burglar-alarm, whereby a cheap and efficient apparatus is obtained, as hereinafter set forth.

In the accompanying drawings,

A is the alarm-bell, and

B b is a metallic case, which holds the actuating-devices for operating the hammers C C.

These operating-devices consist in a central shaft, or pivot, d, to which is fixed a ratchet-wheel, f, (fig. 2,) and a main spring, E, one end of which is fixed to a stud, e, and the other end fastened to the shaft d, and in a detent lever, K, with spring k, one end of said lever K being pivoted to the face, or shell b, and the other end connecting with a trigger, g, which is operated by a cord, I.

The hammers C C are pivoted to arms c c, which project from the shaft d, as shown in fig. 1.

Its operation is as follows:

The main spring E is wound up by placing a key on the shaft d, fig. 1, and the key being turned in direction of the arrows, the hammers fall by their own weight, so as to clear the bell in winding.

The device is then hung on a nail by the side of the door, as shown in fig. 3, and the trigger-cord I attached to the door, in such manner that the cord will release the detent K when the door is moved to open it.

When the ratchet-wheel f is released, the spring E revolves the shaft d rapidly, and the hammers C C are thrown out by centrifugal force, so as to reach the bell and strike it with considerable force. And the hammers, in this manner, do not come in contact with the bell in winding, but are thrown out so as to strike the bell when impelled by the main spring.

The case B b is made of malleable cast-iron usually, and japanned, and the device can be manufactured at a very moderate cost.

Having thus fully described my invention,

What I claim as new, and desire to secure by Letters Patent, is—

The burglar-alarm, composed of the bell A, case B, hammers C C, spring E, shaft d f, and detents K k g, as herein shown and for the purpose described.

The above specification of my invention, signed by me, this 21st day of December, 1867.

CHARLES WILEY.
